HEAT TRANSFER APPARATUS

Edward A. Gurlik, Hamden, Conn., assignor to
The G & O Manufacturing Company, New Ha-
ven, Conn., a corporation of Connecticut

Application March 12, 1938, Serial No. 195,576

6 Claims. (Cl. 257—139)

This invention relates to heat transfer apparatus, and has more particularly in view improvements in apparatus such as used for heating the interiors of automobiles and the like, where air is heated by causing it to pass over a suitable core through which warm water circulates. The invention is not limited, however, to this particular application. The invention also relates more especially to that class of devices in which a suitable core is interposed between tanks or headers, one of which is so divided or partitioned that the water is caused to pass in one direction through one portion of the core and then in the opposite direction through the remaining portion.

15 The primary object of the invention is to improve the construction of the heat transfer apparatus so that it is easier to manufacture the parts and to assemble them, and so that the completed radiator or like article can be produced at minimum expense.

20 In the accompanying drawing:

Fig. 1 is a front elevation, with certain parts omitted, of a heat exchange device embodying my improvements, and such as used in the construction of an automobile heater;

25 Fig. 2 is a side elevation of the device shown in Fig. 1;

Fig. 3 is an enlarged partial section on line 3—3 of Fig. 2;

30 Fig. 4 shows on a still larger scale certain of the parts illustrated in Fig. 3;

Figs. 5 and 6 are sections on lines 5—5 and 6—6, respectively, of Figs. 2 and 1, respectively;

35 Fig. 7 is a detail perspective view of the parti-
tion plate;

Fig. 8 is a detail perspective view of that portion of the header which receives said partition plate; and

Fig. 9 is a transverse sectional view of a header showing a slightly modified partition structure.

40 In the form of my invention shown in the drawing, a radiator core 10 has attached thereto at opposite side edges headers 11 and 12, respectively. Header 12 is divided or partitioned off in the manner hereinafter more particularly de-
scribed, so as to create an upper chamber 13 in communication with the contiguous water pas-
sages of the core, and the lower chamber 14 cut off from chamber 13 but in communication with the water passages contiguous to chamber 14. The result of this arrangement is that, assuming that heated water is introduced into header 12 by way of upper pipe connection 15, such water will traverse the upper portion of the core sub-
stantially horizontally, as indicated by the arrows

16, and pass to header 11 within the upper por-
tion thereof, and will then pass to the lower por-
tion of said header, and thence in a horizontal
direction, as indicated by the arrows 17, to the
lower chamber 14 of header 12, from which lower
chamber the water is carried off by means of the
outlet 18. The air to be heated is caused to flow
through the air passages provided in the core in
the customary manner.

45 A preferred construction of the core 10 is shown 10
in the Oppen and Curelio Patent No. 2,020,957, of
November 12, 1935, and in this case there are pro-
vided generally horizontal zig-zag water passages
19 and a plurality of generally horizontally dis-
posed air passages 20 passing through the core 15
from front to rear, the core being made up of a
plurality of generally loop-shaped sheet metal
units which are assembled side by side, and when
so assembled, create between them the intervening
passages for the circulation of water. Each 20
unit preferably extends from one header com-
pletely to the other and comprises a corrugated
sheet metal strip disposed generally in the form
of a loop and having its ends suitably intercon-
nected. In Fig. 4 of the drawing are shown three
25 of such units, and it will be noted that they are all
of identical structure, but have their end joints
21 arranged in alternating or staggered relation.
Therefore, as regards the portion of the core ad-
jacent header 12, it will be seen that some of the
30 units present adjacent the core their joints 21,
while the alternate ones present flat, wide closed
end portions 22, as shown more particularly in
Fig. 4.

35 The division of the header 12 into separate
upper and lower chambers is accomplished by
providing in said header a partition 23, and it will
be noted that this partition is opposite one of the
flat radiator unit portions 22, and is provided with
a flange 23^a abutted and held against the portion
22, as shown more particularly in Fig. 4.

40 The header 12 preferably comprises a stamp-
ing of elongated rectangular shape presenting a
channeled portion or chamber having an open
top but a closed bottom, sides and ends, the top
45 or open portion being abutted against the core
in the manner shown in Figs. 1 and 3. It will be
observed that a rim or flange 24 extends con-
tinuously about the mouth portion of the header,
and by means of this rim portion the header is
50 soldered to the adjacent end portion of the core
in a manner well understood in the art. The
flange portion 23^a of partition 23 is adapted to lie
flush with this rim 24 and to have end tabs 23^b
55 on the partition flange extend across the rim in

flush position, and for this purpose the tabs 23^b are accommodated in suitable depressions 24^a formed by stamping or bending the rim 24.

The partition 23 is preferably formed of sheet metal, and it is provided at the respective ends of its body portion with rather short and wide tongues 23^c, which are adapted to engage by a snap action and interlock with grooved portions 25 in the sides of the header. The arrangement is such that the partition 23 is pushed into its assembled position in the header and interlocked with the header as a result of the inherent resiliency of the header and partition, which are both made of sheet metal, and in this manner, when the partition is pushed into place in assembling the device, it will not be readily displaced. The inner or bottom edge of the partition preferably engages a raised portion 26 at the bottom of the channel in the header whereby the construction is strengthened, and preferably also the partition is strengthened by the provision of the corrugations 27, as best shown in Fig. 7.

It will be observed that by my improvements the partition or dividing wall 23, when assembled with the header and core, is interposed between said parts, so as to be held in place thereby. In other words, by attaching the header to the core the partition or dividing wall is effectively held in place. Moreover, prior to the assemblage of the header with the core, the partition may be effectively held in assembled relation to the header by the snap interlock, as heretofore described. The header and the core are interconnected by soldering, the device being first dipped at one face of the core and then at the other face, and in this operation the solder runs up between the rim 24 and the core, and effectively unites the parts, and in this operation, also, the solder extends over the tabs 23^b of the partition and effectively solders the partition to the header and to the core at this point, thus providing a very strong and durable connection. The ends of the partition flange, which are extended between the header rim and the core, serve to carry solder to and along the joint between the flange and the core, and permit the production of a satisfactory joint between the margin of the partition and the core along what may be termed the fourth side of the partition.

In the modification shown in Fig. 9, the arrangement of the partition 23^x is such as to impart greater strength to the structure by resisting any tendency of the side walls of the header to separate, or, in other words, be bent away from each other. For this purpose the tabs 23^y on the partition are formed with end extensions 23^z which extend past the rim 24 and are bent down adjacent the free edge of the rim.

While I have described in considerable detail a preferred form which my invention may take, it is to be understood that various changes and modifications may be made in the structure of the device without departing from the principles of my invention or the scope of the appended claims.

What I claim is:

1. In heat exchange apparatus, a sheet metal

header of channeled cross section having grooves in its side walls, a sheet metal partition having tongues at its ends to engage said grooves, said header having a flanged rim, and said partition having a flange overlying said rim, and a core 5 to the end of which said header is applied and to which the header is soldered by means of its rim, said partition flange having its ends interposed between the rim and the core and lying substantially flush with the rim. 10

2. In heat exchange apparatus, a honeycomb core having a plurality of fluid passages, said core comprising units having at one end of the core flat plain closed ends, a partition plate having a flange substantially at right angles thereto 15 extending across the end of said core in substantial contact and alinement with the flattened closed end of one of said units, and a header surrounding and conforming to the partition and having a rim overlying the ends of 20 said flange and soldered to the core.

3. In heat exchange apparatus, a header formed of sheet metal and of channeled cross section and having a flanged rim at opposite sides with depressions therein, the side walls of 25 said header having grooves in their inner surfaces, a sheet metal partition member having short tongues at the ends of its body engaging said grooves and provided with a flange extending along the side of and beyond the ends of 30 its body and engaged in the depressions of the header rim so as to be substantially flush with the rim, and a core to which said rim is soldered.

4. In heat exchange apparatus, a sheet metal header of channeled cross section having grooves 35 in its side walls, a sheet metal partition having tongues at its ends to engage said grooves, said header having a flat rim and said partition having at its inner part a flange extending at its ends and lying flatwise against said rim, and 40 a core having portions abutting and soldered to said header rim and said partition flange, the ends of the partition flange being substantially flush with the rim.

5. In heat exchange apparatus, a core having 45 liquid passages extending to an end thereof, a header having an outstanding marginal rim abutting the margins of the end surface of the core, and a partition for dividing said header into separate chambers, located within and extending across the header, said partition being provided with a flange lying against a core wall which is disposed between certain of said liquid 50 passages, and the ends of said flange being extended between the header rim and the core 55 and serving to carry solder along the joint between the flange and the core.

6. In heat exchange apparatus, a core having liquid passages extending to an end thereof, a header having a rim abutting portions of the 60 end surface of the core, and a partition for dividing the header into separate chambers, located within and extending across the header, said partition being provided with lateral tabs 65 contacting portions of the core and underlying the header rim and soldered to the core and rim.

EDWARD A. GURLIK.
